UNITED STATES PATENT OFFICE.

MARIA F. HEATHCOCK, OF PRINCETON, ILLINOIS:

SKIRT-ADJUSTING DEVICE.

1,071,414.

Specification of Letters Patent.

Patented Aug. 26, 1913.

Application filed July 26, 1911. Serial No. 640,538.

To all whom it may concern:

Be it known that I, MARIA F. HEATHCOCK, a citizen of the United States, residing at Princeton, in the county of Bureau and 5 State of Illinois, have invented new and useful Improvements in Skirt-Adjusting Devices, of which the following is a specification.

This invention relates to skirt adjusting devices, and has for an object to provide means whereby the skirt can be conveniently and accurately raised so as to be held at any desired distance from the ground and thereby guard against the unnecessary injury to the skirt, incident to the dragging of the same on the ground.

Another object of the invention is to provide means whereby all portions of the skirt can be uniformly lifted.

20 In the drawing, forming a portion of this specification and in which like numerals of reference indicate similar parts in the several views:—Figure 1 is a view illustrating the application of the invention. Fig. 2 is 25 a view looking at the inner side of a portion of the skirt showing the application of the invention thereto. Fig. 3 is a section through the fastening device showing the application of the same to the lifting cords. Fig. 4 is a perspective view of the device. Fig. 5 is a perspective view showing a slightly modified form of the invention.

My improved adjusting device may be used in connection with any well known 35 form of skirt, the skirt A herein illustrated being provided with the usual placket B and the draw-string C. At each side of the waistband of the skirt is an eyelet D. The main lifting cords or tapes 1 extend downwardly through the eyelets D and are disposed on the inner side of the skirt. These cords are provided at their lower ends with eyes 2 which are fitted in the hooks 3 adjacent to the bottom of the skirt. Supplemental cords or tapes 4 are attached, at 45 5, to the main lifting cords 1, and as shown, these cords are also provided at their lower ends with eyes 5 which are engaged with hook members 6, as shown. These hook members are disposed in line with the hereinbefore described hook members so that the effective points of attachment of the main and supplemental cords will be disposed in the same general plane. Eye members 7 are

disposed above the hook members and are 55 attached to the skirt immediately on the line of the seams of the breadths of the skirt, it being understood, that the lifting cords of the skirt herein shown are equal the number of breadths in the skirt. By providing the 60 skirt with the upper eye members 7 and by arranging the said upper eye members immediately above the points of attachment of the lifting cords the skirt may be uniformly lifted when the central or main lift- 65 ing cords are drawn upwardly. The upper terminals of the main lifting cords are provided with buttons and after the skirt has been lifted to the desired extent the button ends of the cords are tied together at the 70 front of the waist.

The main lifting cords 1 are provided with such attaching devices as those shown at 8. The said attaching devices are of hollow form providing a socket portion 9 the 75 top peripheral edge of which is cut at intervals to form at its outer walls substantially V-shaped slots 10, said slots terminating from the peripheral top edge portion to a point adjacent the reduced extended neck 80 portion 10'. The said attaching devices are each provided with a socket portion 9, the walls of which having formed therein substantially V-slots 10. The supplemental cords have their upper ends knotted, at 11, 85 and as shown, they are fitted in the socket member and confined therein by bending the walls of the socket member over on the knotted ends of the said supplemental cords, as shown at 12. In order to prevent longitudinal sliding of the socket members on the main lifting cord, the said cord is knotted, at 13 and 14, one of said knots 13 engaging with the inner bottom portion of the member 9 while the other knotted portion 14 abuts 90 against the free end and beneath the neck portion 10' to form stops. By close examination of the drawings, and particularly to Fig. 3 it will be seen that when the angle of the supplemental cords are changed the 100 heads of said cords arrange themselves in a position to accommodate the new angle of the supplemental cords, so that there will be no angle formed between the ends of the cords by the change of the direction of the 105 supplemental cords.

In lieu of the socket members shown herein, supplemental cords may be secured to

the main lifting cord by sewing the same thereto, as shown at 15 in Fig. 5 of the drawing.

I claim:

- 5 A skirt adjusting device comprising a main vertical cord, an upwardly opening hollow semi-spherical body provided with an opening in its bottom through which the cord passes, a cylindrical extension at the 10 bottom of said body through which the cord passes, a knot formed in the cord and engaging the upper side of the bottom of the body, another knot formed in the cord and engaging the lower end of the extension, said 15 knots securing the body against movement lengthwise on the cord, relatively spaced

fingers rising vertically from the upper edge of the body to provide a plurality of cord engaging notches, and supplemental cords knotted at their free ends and having said 20 knots disposed in the semi-spherical body, and said cords leaving the body through the said cord receiving notches, the said fingers being bent inward to retain the knots of the supplemental cords within the body. 25

In testimony whereof I affix my signature in presence of two witnesses.

MARIA F. HEATHCOCK.
